UNITED STATES PATENT OFFICE.

HERMAN C. KREIPKE, OF LOS ANGELES, CALIFORNIA.

DOUBLE-ACTING DOORCHECK.

Application filed April 17, 1924. Serial No. 707,127.

To all whom it may concern:

Be it known that I, HERMAN C. KREIPKE, a citizen of the United States, residing at Los Angeles, in the county of Los Angeles and State of California, have invented new and useful Improvements in Double-Acting Doorchecks, of which the following is a specification.

This invention relates to double acting door checks.

An object is to make a door check for swinging doors which will automatically hold a swinging door open either way, and which will automatically hold a swinging door yieldingly closed.

Another object is to make a door check having an air dash pot, a dash pot piston in the dash pot, and a restoring spring in opposition to the air in the dash pot, to mount the dash pot on a door and to provide a crank and gear connection between the dash pot on the door and a part of the door frame.

Other objects and advantages will appear from the drawings and specification.

The drawings illustrate the invention and its application and use.

Figure 1 is a horizontal fragmentary sectional detail through a door and door frame and showing a double acting door check embodying the principles of my invention in use, the view being taken on the line 1—1 of Fig. 2, and looking downwardly as indicated by the arrows.

Fig. 2 is a fragmentary sectional elevation on the line 2—2 of Fig. 1 and looking in the direction indicated by the arrows.

Fig. 3 is a fragmentary diagrammatic plan view showing in full lines the door held wide open one way, in dotted lines the door held closed, and in second dotted lines the door held wide open the other way, by the use of my invention.

Referring first to Fig. 2, the door 1 is mounted in the door opening 2 in the door frame 3, and is adapted to swing both ways from its closed position upon the pintle 4 fixed in a vertical position and connecting the door to the horizontal rail 5 of the door frame and the pintle 6 mounted in vertical alinement with the pintle 4 and connecting the door to the floor part 7 of the door frame. An attaching plate 8 is recessed into the floor 7 and secured in place by screws 9, and has an upwardly extending spacing hub 10. The segmental gear 11 is mounted upon

the upper face of the hub 10 and held in place by screws 12. The post 13 is fixed in the plate 8 and has an enlarged portion 14 fitting in the hub at the axial center of the gear 11 and forming a shoulder 15 at its upper end and the pintle 6 extends upwardly from the shoulder.

A recess 16 is formed by cutting away the lower corner of the door 1 for a considerable distance longitudinally, a housing plate comprising a bottom 17, sides 18 and 19, and an end 20, covers the recess 16 and is rigidly secured in place by screws 21, 22 and 23. The pintle 6 extends through the bottom 17 and the upper end of the pintle is screw threaded and a washer and nut is applied above the bottom 17 to make a loose connection so that the door will swing freely. A bearing bracket 24 has a main portion parallel with the bottom 17 and a downwardly turned portion fitting against the inner face of the end 20 and secured in place by bolts or rivets 25. A crank shaft 26 is mounted rotatably through the bracket 24 and through the bottom 17 and a spur pinion 27 is fixed upon the lower end of the crank shaft 26 against the lower face of the bottom 17 in mesh with the segmental gear 11. A pitman or link 28 is mounted upon the crank 29 of the crank shaft 26.

A dash pot cylinder 30 has heads 31 and 32 mounted upon the upper face of the bottom 17 and secured in place by screws 33 and 34, an intake check valve construction 35 is mounted in and through the head 32, a dash pot piston 36 is mounted in the cylinder 30, and a piston rod or stem 37 extends from the piston 36 slidably through the head 31 and is connected to the pitman 28 by a pivot pin 38. An expansion spring 39 is mounted in the cylinder 30 between the piston 36 and the head 31. The dash pot chamber 40 between the piston 36 and the head 32 is adapted to take in air through the check valve 35 when the piston 36 is moved away from the head 32, and the tension of the spring 39 is exerted in opposition to the pressure of the air in the chamber 40 when the piston 36 is released, and provision may be made for the surplus air pressure escaping from the chamber 40 by leaking around the piston 36 or in any other suitable way, as by a small port 41. A similar port 42 is formed through the head 31 to allow the air to escape from the chamber 43 in which the spring 39 operates.

Referring to Fig. 1, when the door is in closed position the crank 29, the pitman 28, the piston rod 37 and the door 1 are all in a straight line at right angles to the face 44 of the side frame 3 and the walls 45 and 46 extend both ways from the frame 3. Any movement swinging the door either way from the closed position will move the crank 29 one way or the other to pull the piston 36 against the spring 39, and when the door is released the tension of the spring will return the door to its normal closed position and the air pressure in the chamber 40 will form a resistance to prevent the door 15 from slamming or quick action.

When it is desired to hold the door wide open one way, as shown in full lines in Fig. 3, the crank shaft 26 carrying the crank 29 is operated by the pinion 27 engaging the 20 segmental gear 11, the pinion 27 rotating in the direction indicated by the arrow 47 until the crank 29 passes the dead center and then the tension of the spring 39 pulling upon the crank 29 will swing the door 25 wide open against the wall 45 and hold it in that position until the door is manually moved to swing the crank 29 backwardly past the dead center. In a like manner, when the door is swung wide open in the 30 opposite direction as indicated in dotted lines in Fig. 3, the pinion 27 will be rotated in the opposite direction as indicated by the arrow 48 until the crank 29 passes the dead center and the tension of the spring 39 will 35 hold the door wide open in this position, the door pressing against the wall 46. When the door is swung from either wide open position until the crank 29 passes the dead center in the direction opposite to the arrows 47 and 48, the tension of the spring 39 will 40 swing the door to its closed position as shown in Fig. 1, and as shown in the dotted lines 49 in Fig. 3.

The door frame side 3^a is in opposition 45 to the side 3 and the door opening 2 is between the frame sides 3 and 3^a. If the door opening 50 happens to be some distance from a wall, of course there would be no walls 45 and 46 for the door to swing against when opened.

The sides 18 and 19 are bulged outwardly to form the housing members 18^a and 19^a at opposite sides of the gears and as required

to allow the crank shaft 26 to rotate. When the walls 45 and 46 are not present, the door 55 may swing open either way until the housings 18^a or 19^a strike the face 44 of the frame side 3 and the tension will hold the door open the same as though the door was swinging against a wall 45 or 46 or some 60 other stop.

While I have shown the details of one complete and satisfactory double acting door check and its operation, it is obvious that various changes may be made without 65 departing from the spirit of the invention as set up in the following claims.

I claim:

1. The combination with a door frame and a door mounted in the frame and adapted to swing wide open in either or both directions, of a double acting door check comprising a dash pot cylinder adapted to be mounted on a door, a dash pot piston in the cylinder, a spring pressing the dash pot 70 piston against the pressure in the cylinder, a stem for operating the dash pot, piston, a crank connected to the stem, a spur gear upon the crank, and a segment of spur gear adapted to be fixed to the door frame concentric to the axis upon which the door swings and meshing with the spur gear upon the crank, the crank, the stem, the piston rod and the door being all in a straight line at right angles to the face of 75 the door frame when the door is closed and the tension of the spring being exerted to hold the door closed and when the door is swung wide open either way the tension of the spring pulling upon the crank will hold 80 the door wide open.

2. A double acting door check comprising a dash pot cylinder adapted to be mounted on a door, a dash pot piston in the cylinder, a spring pressing the dash pot piston against 85 the pressure in the cylinder, a stem for operating the dash pot piston, a crank connected to the stem, a spur gear upon the crank, and a segment of spur gear adapted to be fixed to the door frame concentric to 90 the axis upon which the door swings and meshing with the spur gear upon the crank.

In testimony whereof I have signed my name to this specification.

HERMAN C. KREIPKE.
